EDWARD L. STUCK, OF ROTHSCHILD, WISCONSIN.

REINFORCEMENT FOR PAPER CORES.

1,180,955.

Specification of Letters Patent. Patented Apr. 25, 1916.

Application filed March 30, 1915. Serial No. 17,985.

To all whom it may concern:

Be it known that I, EDWARD L. STUCK, a citizen of the United States, and a resident of Rothschild, in the county of Marathon 5 and State of Wisconsin, have made an Improvement in Reinforcements for Paper Cores, of which the following is a specification.

My invention is an expandible reinforcement and stiffener for the tubular paper cores or bodies on which paper rolls are wound. Such cores are usually made of paper or some like material, and are provided with reinforcements which are riveted 10 in place and are hence not detachable, but permanently associated with the core.

My expandible and detachable reinforcement is constructed of sheet metal, preferably steel, and divided longitudinally, the 20 opposing edges being bent to form hooked flanges which are directly opposite each other and provide a keyway adapted to receive a wedge-shaped key, which, when driven in, expands the reinforcement so that 25 it fits tightly in the paper core but may be readily contracted and removed by detaching the wedge.

The details of construction, arrangement 30 and operation of parts comprising the invention are as hereinafter described and illustrated in the accompanying drawing, in which,

Figure 1 is a longitudinal section showing my improvement applied to a tubular paper 35 core and the shaft on which it is used. Fig. 2 is a perspective view of disassociated members of the invention. Fig. 3 is an enlarged cross section on the line 3—3 of Fig. 1. Fig. 4 is an enlarged cross section of the core 40 with the body of the reinforcement applied therein.

In Fig. 1 the numeral 1 indicates a shaft and 2 a paper cylindrical tubular core mounted thereon, the core being such as 45 paper rolls are usually wound upon.

My expandible steel reinforcement 3— shown in perspective in Fig. 2—is practically a short hollow cylinder whose opposing edges are bent inwardly and at such angles 50 as to form a key-way adapted to receive a wedge-shaped key 4, shown also disassociated in Fig. 2. Such reinforcement is applied at each end of the core 2, as shown in Fig. 1, and, upon driving in the wedges 4, 55 the reinforcements are expanded and firmly

support the body of the core 2. In order to connect the reinforcement and core with the shaft 1, a collar 5 is applied at each end of the core, the same being shown, in Figs. 1 and 2, as provided with a flanged head and 60 a key-way 6 adapted to receive the flanges 3^a of the reinforcement and the key or wedge 4. The collars 5 may be keyed to the shaft 1 in any required manner which will adapt it 65 for convenient adjustment on the shaft. They thus form practically enlargements of the shaft at the ends of the core.

It is apparent that, upon inserting the reinforcements 3 in the ends of the core 2, and then driving in the wedges 4, the reinforcements are fully expanded and grip the core 70 with the required force so as to hold the same rigidly expanded. Then, upon adjusting the collars 5 with the key-way 6 in coincidence with the flanges 3^a of the reinforcements, the collars may be shoved up 75 into the position indicated in Fig. 1. With the parts thus adjusted, the core may be revolved for winding paper upon it in the usual way.

I desire it understood that the expandible reinforcements which I employ may be connected with the shaft by any other means than those I have illustrated, the main feature of my invention being the provision of 85 a light, expandible reinforcement which may be made to fit tightly within the core and is easily detached therefrom. I thus provide a very efficient, cheap, and easily applied and 90 removed attachment which enables a comparatively thin and light paper core to be successfully employed. After the paper has been wound thereon to form a roll of the required diameter, the reinforcement may be quickly removed and used over again in 95 other rolls.

I claim:

The combination, with a tubular core, a shaft, and a collar mounted thereon and having a longitudinal key-way, of a reinforcement comprising a metal tube divided longitudinally and having its separated edges bent inward and toward each other to form a key-way fitting in said collar keyway, and a wedge adapted for insertion in such key- 100 ways, as described.

EDWARD L. STUCK.

In presence of—
ROBERT SCHMIDT,
MARGARET RYAN.
